SHOE SOLE

Bertram H. MacLeod, Red Wing, Minn., assignor to Avon Sole Company, Avon, Mass., a corporation of Massachusetts

Application January 9, 1958, Serial No. 49,177

Term of patent 14 years

(Cl. D7—5)

Fig. 1 is a plan view of a shoe sole showing my new design; and

Fig. 2 is a cross sectional view taken along the line 2—2 of Figure 1.

I claim:

The ornamental design for a shoe sole as shown.
